2,454,299

FINISHING MACHINE FOR ORNAMENTAL CHAINS

Ferdinand Armbrust, Hoxie, R. I., assignor to
Armbrust Chain Company, a corporation of
Rhode Island

Application May 16, 1947, Serial No. 748,481

4 Claims. (Cl. 51—137)

1

The present invention relates to chain machines, and has particular reference to a novel construction for a finishing machine.

The principal object of the invention is to provide a machine for flat finishing ornamental chains and the like.

A further object of the invention is to provide an apparatus for finishing both sides of an endless length of chain in a continuous process.

Still other objects of the present invention are to provide a finishing machine which is simple in construction, is easily assembled and maintained, and has a long and effective life.

With the above and other objects and advantageous features in view, the invention consists of a novel arrangement of parts more fully disclosed in the detailed description following, in conjunction with the accompanying drawings, and more specifically defined in the claims appended thereto.

In the drawings:

Fig. 1 is a plan view of an illustrative machine embodying the invention, parts being omitted;

Fig. 2 is an end view of the machine;

Fig. 3 is a side elevation thereof, parts being broken away;

Fig. 4 is an elevation of the other side thereof;

Fig. 5 is a perspective view of the guide roll carriage;

Fig. 6 is a fragmentary view of one guide roll carriage support;

Fig. 7 is a perspective view of the base of one tensioning device;

Fig. 8 is a perspective view of the cover therefor;

Fig. 9 is a disassembled perspective view of the finishing wheel;

Fig. 10 is a plan view of the helical guide;

Fig. 11 is a perspective view of the friction roller;

Fig. 12 is a view of a curb chain section before filing; and

Fig. 13 is a similar view of the chain section after filing.

In manufacturing ornamental jewelry chains, it is desirable to enhance the ornamentation of the chain by finishing the links to achieve a flattened effect, this finishing being particularly applicable to curb chains. The flattened effect has heretofore been achieved by hand or by a mechanical process involving the use of multiple machines, and the present invention is designed to provide an inexpensive machine which will flat finish an endless length of chain in one continuous operation.

2

Referring to the drawings illustrating the invention, and particularly Figs. 1 and 4 thereof, the machine is preferably mounted on a base or table 20 of generally rectangular shape. A chain 21 is provided which is fed into the apparatus from a source of supply not shown, and preferably positioned below the level of the base 20. The chain is fed into the machine from the lower left hand corner, looking at Fig. 1, and passes over a guide rod 22 which is mounted on an adjustable bar support 23 bolted to the edge of the table 20. The chain passes through a tensioning device 24 which is mounted on one side of the support 23 and is adapted to frictionally releasably permit the chain to be pulled into the machine under tension, and around an idling pulley 25 and over a guide pulley 26, which is mounted for both vertical and radial adjustment. The chain then passes under a finishing wheel 27 which is adapted to rotate in a direction opposite the path of movement of the chain and to finish the top of the chain as it passes beneath the wheel. The chain then passes over a second guide pulley 28, and across to a friction roller 29 provided with a grooved surface 30 which is adapted to frictionally engage the chain as it is wound thereon. The roller 29 pulls the chain 21 through the machine counter to the movement of the finishing wheel 27, the tensioning device 24 resisting the movement of the chain and providing a suitable tension.

A helical guide 31 is loosely mounted on the friction roller 29 and provides a spiral chain track which causes the chain to follow a helical path on the roller 29 and come off the end of the roller after making enough turns to provide an effective friction grip.

A sufficient length of chain is now permitted to extend downwardly into a container or receptacle on the floor (not shown) and the chain is then fed across a second guide bar 32, positioned at the lower right hand corner of the machine as shown in Fig. 1. The chain is passed over the guide bar 32 with the already finished side on top. The guide bar 32 is fixed to an adjustable bar support 33, bolted to the side of the table 20, similarly to the bar support 23. The chain now passes through a second tensioning device 34, similar to the tensioning device 24, and around an idler pulley 35 and a guide pulley 36, similar to the idler pulley 25 and guide pulley 26. This brings the unfiled side of the chain upwardly, and the chain now passes beneath a second finishing wheel 37, which is like the wheel 27, and is also rotated in a direction opposite the

path of movement of the chain. The chain passes over a guide pulley 38, similar to the guide pulley 28, and is wound on a friction roller 39 which is similar to the friction roller 29, and has a grooved surface 40 formed by a loosely mounted helical guide 41, similar to the guide 31, and providing a spiral chain track.

The chain is evenly finished and the finishing wheels 27 and 37 are prevented from wearing along a fixed groove by imparting a reciprocating motion to the chain as it passes beneath each finishing wheel, as hereinafter explained.

The power mechanism

The machine is driven from a source of motive power 42 which is supported on a frame 43 on the table 20, see Fig. 4. The motor 42 drives a sprocket wheel 44 and chain 45 which in turn drives a sprocket wheel 46 mounted on a shaft 47 which is journaled in spaced bearing brackets 48 and 49 extending from a base 50 mounted on the table 20. The finishing wheels 27, 37 are keyed to the ends of the shaft 47, and includes a base portion 51 of soft felt, having a central opening 52 which fits over a boss 53 on one side flange 54 of the finishing wheel, see Fig. 9. A second flange 55 is provided, and the two flanges have central openings 56, 57 to permit the assembled wheels to be slipped onto reduced ends 58, 59 of the shaft 47 for abutting against the larger diameter central portion, washers 60 and nuts 61 being threaded on the reduced shaft ends to lock the finishing wheels in place. An abrasive belt 62 extends over each felt base portion 51 between the wheel flanges, and is given proper tension by an idler pulley 63 which is rotatably mounted on a shaft 64 mounted on a rod 65 pivotally secured to one upright leg or column 66 of the motor support frame 43. A tension spring 67 is secured to the lower end of the rod 65 and its operative end is attached to the frame 43 to maintain the belt 62 at proper tension. The sprocket wheel 44 is of larger diameter than the sprocket wheel 46 to rotate the finishing wheels at higher peripheral speed than the linear speed of the contacted chain.

The shaft 68 of the motor 42 is connected through a coupling 69 to a gear reduction box 70 of standard construction, which is also mounted on the frame 43, as shown in Fig. 4, and actuates a V-pulley 71 which is connected by a belt 72 to a larger pulley 73 mounted on the end of the cross shaft 74, see Fig. 1, which carries the friction rollers 29 and 39. The belt tension is adjusted by an idler pulley 75 which is rotatably mounted on a slotted bar 76 slidably secured to the frame 43. This arrangement results in a very slow rotary motion of the friction rollers 29 and 30, as compared to the high speed rotary motion of the finishing wheels.

The chain reciprocating mechanism

The mechanism for reciprocating the chain under the finishing wheels includes a guide roll carriage 77 which is preferably made in two sections 78, 79 secured together, as illustrated in Fig. 5, the carriage being mounted for reciprocating movement on brackets 80 which extend from the frame 50; the parallel upper bars 81 pass over the brackets and are slidably secured thereto by overlapping plates 82, as shown in Fig. 6, and the ends 83 carry adjustable slotted arms 84 which carry the pulleys 26, 28 and 36, 38. The idling pulleys 25 and 35 are

rotatably mounted on extensions 85 at the rear of the ends 83, see Fig. 5.

The carriage 77 is reciprocated through an adjustable link 86, see Fig. 2, which is pivoted to a yoke 87 fastened to one end 83 of the carriage 77, as shown in Fig. 5, and the other end of the link 86 is pivoted to an eccentric 88 which is mounted at the end of a shaft 89 at the side of the machine, which is driven through gear 90, gear 91, stub shaft 92 and bevel gears 93, 94 from the shaft 74. Rotation of the eccentric 88 oscillates the link 86 and reciprocates the carriage 77 and moves the chain 21 across the face of both finishing wheels.

The tensioning mechanism

The friction rollers 29 and 39 are both keyed to the shaft 74 and rotate simultaneously and at the same speed, and the helical guides 31 and 41 are preferably loosely mounted on the rollers and are made of rectangular wiring bent into a helix of slightly larger diameter than the friction rollers, thus forming spiral chain tracks; the guides have one end 95 extended downwardly to abut the edge of the table 20, see Fig. 2, to prevent rotation of the guides while the friction rollers are rotating.

The tensioning devices 24 and 34 are shown in detail in Figs. 7 and 8, and comprise a base portion 96, preferably of fiber, provided with an upper longitudinal channel 97 through which the chain 21 passes. A T-shaped cover 98 of the same material is placed over the base portion 96 with its central depending tongue 99, which is slightly longer than the depth of the channel 97, extending into the channel 97. The cover 98 is held on the base portion 96 by threaded rods 100 which extend through the cover and are threaded into the base, coil springs 101 being positioned between the top of the cover and end nuts 102 on the rods to resiliently adjustably hold the cover on the base portion. As the chain passes through the channel 97, it is resiliently and frictionally retarded by the depending tongues 99 of the covers to maintain the chain taut.

The invention thus provides a power connection between the power shaft and the finishing wheel shaft, whereby the finishing wheel is positively driven in correspondence with the motor speed. The preferred drive is through sprocket wheel arrangements, but belt drives may be used for light finishing work. The chain feed is driven through the medium of a reduction gearing and a belt driven pulley, the belt being maintained under suitable tension, whereby the chain is pulled into contacting engagement with the face of the finishing wheel, the pulling being sufficiently flexible to permit slight variations in the speed of feeding and thus compensate for variations in chain conditions and the like.

Preferably, the mechanism for reciprocating the fed chain while it is in contacting engagement with the finishing surface of the finishing wheel, is operated in timed relation to the feeding of the chain, whereby the speed of feeding and the reciprocation correspond. Further, the finishing wheel preferably utilizes a flexible finishing belt under regulated tension, thus providing longer life for the finishing surface and obviating the need for frequent replacements.

While I have described a specific embodiment of the invention, it is obvious that changes in the size, shape and material of the parts may be made to suit the requirements for different finishing

machines for ornamental chains, without departing from the spirit and the scope of the invention as defined in the appended claims.

I claim:

1. In a chain finishing machine, a power shaft, a finishing wheel shaft, a finishing wheel keyed to said finishing wheel shaft, means for positively driving said finishing wheel shaft from said power shaft, a chain feed shaft, chain feeding means on said shaft, means for driving said chain feed shaft at a reduced speed from said power shaft, including a belt driven pulley, means for guiding a chain fed by said chain feeding means into contacting engagement with said finishing wheel, means for maintaining the guided chain under tension, and means for reciprocating the guiding means to move the contacting chain over the face of the finishing wheel.

2. In a chain finishing machine, a power shaft, a finishing wheel shaft, a finishing wheel keyed to said finishing wheel shaft, means for positively driving said finishing wheel shaft from said power shaft, a chain feed shaft, chain feeding means on said shaft, means for driving said chain feed shaft at a reduced speed from said power shaft, means for guiding a chain fed by said chain feeding means into contacting engagement with said finishing wheel, means for maintaining the guided chain under tension, and means for reciprocating the guiding means to move the contacting chain over the face of the finishing wheel, said finishing wheel carrying a flexible finishing belt, and means for keeping said belt under tension.

3. In a chain finishing machine, a power shaft, a finishing wheel shaft, a finishing wheel keyed

35

to said finishing wheel shaft, means for positively driving said finishing wheel shaft from said power shaft, a chain feed shaft, chain feeding means on said shaft, means for driving said chain feed shaft at a reduced speed from said power shaft, including a reduction gearing and a belt driven pulley, means for guiding a chain fed by said chain feeding means into contacting engagement with said finishing wheel, means for maintaining the guided chain under tension, and means for reciprocating the guiding means in timed relation to the chain feeding means to move the contacting chain over the face of the finishing wheel.

4. In a chain finishing machine, a power shaft, a finishing wheel shaft, a finishing wheel keyed to said finishing wheel shaft, means for positively driving said finishing wheel shaft from said power shaft, a chain feed shaft, chain feeding means on said shaft, means for driving said chain feed shaft at a reduced speed from said power shaft, including a reduction gearing and a belt driven pulley, means for guiding a chain fed by said chain feeding means into contacting engagement with said finishing wheel, means for maintaining the guided chain under tension, and means for reciprocating the guiding means in timed relation to the chain feeding means to move the contacting chain over the face of the finishing wheel, an idler pulley, a flexible finishing belt mounted on said idler pulley and said finishing wheel, and means for keeping said belt under tension.

FERDINAND ARMBRUST.
